UNITED STATES PATENT OFFICE.

CHARLES H. PELTON, OF SPRINGFIELD, OHIO.

DESIGN FOR A DRIVING-DISK.

SPECIFICATION forming part of Design No. 24,368, dated June 4, 1895.

Application filed February 1, 1895. Serial No. 537,016. Term of patent 14 years.

To all whom it may concern:

Be it known that I, CHARLES H. PELTON, a citizen of the United States, residing at Springfield, in the county of Clark and State of Ohio,

5 have invented and produced a new and original Design for a Driving-Disk, of which the following is a specification, reference being had to the accompanying drawings, showing the same.

10 In the drawings, Figure 1 is a plan or face view of my driving-disk. Fig. 2 is a side elevation of the same.

The leading feature of my design consists in a flat faced circular disk provided with concentric rows of crescent shaped or semi-cylindrical projections, projecting at right angles 15 from the face of the disk and occupying an equidistant position in each row, the open

sides of said projections being on a line radial with the disk which gives to the disk a novel and pleasing appearance both when viewed in plan or in side elevation.

A, is the disk with a flat face. *a* and *b* are the crescent shaped or semi-cylindrical projections from the face of the disk and arranged at equal distances apart in concentric rows.

In Fig. 2, *e* is the hub of the disk and in Fig. 1 *d* is the bore for the shaft.

Having thus described my design, what I claim is—

30 The design for a driving disk, substantially as shown and described.

CHARLES H. PELTON.
